[57] CLAIM

The ornamental design for a peace-pipe pendant or
similar article, as shown and described.

DESCRIPTION

FIG. 1 is a perspective view of the peace-pipe pendant
or similar article showing my new design;
FIG. 2 is a front elevational view of the article of FIG.
1 on an enlarged scale;
FIG. 3 is a top plan view of the article of FIG. 1 on an
enlarged scale; and
FIG. 4 is a bottom plan view of the article of FIG. 1 on
an enlarged scale.
